No. 36,731.

Patented January 12, 1904.

UNITED STATES PATENT OFFICE.

JOHN EHRENPREIS, OF CHICAGO, ILLINOIS, ASSIGNOR TO THE BRUNSWICK-BALKE-COLLENDER COMPANY, OF CHICAGO, ILLINOIS, A CORPORATION OF OHIO.

DESIGN FOR A DRINKING COUNTER, OR BAR PROPER, FOR BAR-FIXTURES.

SPECIFICATION forming part of Design No. 36,731, dated January 12, 1904.

Application filed December 4, 1903. Serial No. 183,833. Term of patent 14 years.

To all whom it may concern:

Be it known that I, JOHN EHRENPREIS, a citizen of the United States, residing at Chicago, in the county of Cook and State of Illinois, have invented a new, original, and ornamental Design for a Drinking Counter or Bar Proper of a Bar-Fixture.

The accompanying drawing is a perspective view of my new design for a drinking counter or bar proper.

What I claim as my invention is—
The ornamental design for a drinking counter, or bar proper, of a bar-fixture herein shown.

JOHN EHRENPREIS.
